UNITED STATES PATENT OFFICE.

FRED RICKS AND ALFRED EDWARD RICHARDS, OF LEICESTER, ENGLAND, ASSIGNEES
TO UNITED SHOE MACHINERY CORPORATION, OF PATERSON, NEW JERSEY, A
CORPORATION OF NEW JERSEY.

SHOE-SOFTENING APPARATUS.

Application filed January 18, 1922, Serial No. 530,151, and in Great Britain January 25, 1921.

This invention relates to the art of softening parts of boots and shoes in process of manufacture and is herein exemplified with especial relation to preparing, regulating, 5 and administering softening media to the toes of boots and shoes.

In one respect an object of the invention is to meet the requirements of boot and shoe manufacturers who, through choice or necessity, use combustible gas to furnish the heat for such treatment. With this requirement in view the invention provides an apparatus comprising one or more treating chambers into which the shoes are inserted, a boiler 10 for water, a gas burner for heating the water in the boiler so as to convert it into moist vapor to supply one of the treating media, and a novel arrangement of ducts by which the hot products of combustion and 15 the moist vapor may be intermingled in variable proportions before entering the treating chamber or chambers. So far as we are aware, hot products of combustion have never heretofore been used for this 20 purpose.

Other features of the invention as exemplified by the accompanying drawings consist in a gas burner arranged under a pressure-sustaining boiler, a treating chamber 25 arranged above the boiler, a flue extending from the combustion space to the treating chamber, and a vapor duct extending from the steam space of the boiler to the aforesaid flue. By this combination of elements 30 the dry hot products of combustion are conducted to the treating chamber to treat those elements of the work that become soft when heated, but these heated gases may be tempered more or less, before reaching the work, 35 by the moist vapor that passes from the steam space of the boiler into the flue through which the products of combustion pass.

Another object of the invention is to meet 40 various requirements of all the different kinds of leather and stiffening materials generally used in the manufacture of boots and shoes, as by providing a softening apparatus with which dry heat alone, moist vapor alone, or dry heat and moist vapor 45 combined in various proportions subject to

regulation may be supplied to the materials to be treated.

To this end, another feature consists in arranging dampers to control the admission 55 of the products of combustion and the moist vapor respectively to a flue so that each may be regulated independently of the other even to the extent of entirely shutting off either.

A further feature consists in making the control for the steam in the boiler in such manner that it will relieve excess pressure in inverse proportion to the relief afforded by communication with the passageway that 65 leads to the treating chamber. This obviously guards against dangerously high pressure in the boiler without wasting the steam when the latter is required for treatment of the work.

Another feature consists in arranging the aforesaid flue to extend through the boiler so that it will be entirely surrounded by the water and steam in the boiler thus utilizing the hot products of combustion most economically with regard to generating steam and also most advantageously to reduce the temperature of the gases to a degree that will not be injurious to the work. Still another feature consists in arranging a 75 water reservoir for the boiler in such position that it will be heated by the exhaust steam and products of combustion, thereby increasing the efficiency and economy of the apparatus.

Other objects of the invention are herein-after described and claimed and other features are shown by the accompanying drawings.

Referring to the drawings,

Fig. 1 is a front elevation of an apparatus constructed in accordance with this invention;

Fig. 2 is a side elevation thereof; and

Fig. 3 is a top plan view.

An oblong boiler 3 constitutes a base for a superstructure 5 which consists essentially in a casing including a water reservoir 7 and a plurality of treating chambers each of a shape and size adapted to receive the fore-part of a shoe. The structure 5 may be lifted from the boiler whenever necessary

but is fastened to the latter by a flexible metal strap 9 the ends of which are provided with pivot bolts 11 adapted to be slipped through bosses 13 formed on a supporting stand 67. Wing nuts carried by the bolts 11 serve to tighten the strap. The water reservoir is provided with a hinged cover 15, which, when lifted, uncovers an opening through which water may be poured. The bottom of the reservoir is indicated at 17 and preferably slopes toward the front. The treating chambers are at the front of the structure 5 and are divided by a partition 24 from an exhaust chamber 51 through which the waste steam, vapor, and products of combustion are obliged to pass so as to give up a considerable quantity of heat to the bottom wall 17 of the reservoir before they escape from the chamber through the exhaust port 19.

Water for supplying the boiler 3 is discharged from the reservoir 7 through a cock 21 which discharges into an open funnel 23 on the front of the boiler. The front wall 25 of the structure 5 has four arched openings to receive the shoes, the edges 27 of said openings being beaded to guard against damaging the shoes. These arched openings lead respectively to individual treating chambers each of which will receive only one shoe. Each treating chamber is formed, for the most part, by an arched sheet 29, preferably made of heat-insulating material such as asbestos. These sheets 29 extend from the front wall of the structure 5 to the partition 24. The bottoms 31 of the treating chambers are formed to permit the treating media to pass through them and may be made of wire fabric. The front edges 33 of the members 31 are in contact with the front wall of the structure 5 while the rear edges 35 are in contact with the partition 24. The arched members 29 and the bottom members 31 may be put together separately to form units and inserted through the open bottom of the structure 5 before the latter is mounted on the boiler. When the apparatus is fully assembled they are supported by the top of the boiler and are held in place partly by the partition 24, partly by the front wall of the structure 5, and partly by contact with each other. If desired, the arched members 29 may be reinforced by sheathing 32 of sheet metal. The openings 37 through which the waste treating media escape from the treating chambers are defined by the arched members 29 and the upper edge 25 of the partition 24.

Flues 39 extend through the boiler from bottom to top and are open at both ends, their upper ends being in registration respectively with the treating chambers, one flue being provided for each chamber. These flues conduct the hot products of combustion from a gas burner 61, 63, to the

treating chambers, but if it were desired to provide another type of heating means, such as one or more electric units, in substitution for the gas burner the air heated thereby would pass through the flues 39.

70

A trunk 41 is arranged to extend horizontally in the upper part of the boiler and is closed at its ends. Its purpose is to conduct steam from the steam space of the boiler to the flues 39, and it is therefore connected to the flues by branches or ducts 43. Communication between the steam space and the interior of the trunk 41 is controlled by a rotary valve the plug 45 of which is open at its end 47 to receive the steam and has a port in its side to release the steam into the trunk or into the exhaust nozzle 49, as the case may be, depending upon the position to which it is turned. In fact, the valve is so formed that it never entirely 85 closes the communication between the steam space and the atmosphere, and therefore prevents excessive pressure from being developed in the boiler. Furthermore, as the valve is turned it varies inversely the area 90 of communication with the trunk 41 and the area of communication with the exhaust nozzle 49. The nozzle 49 is arranged to discharge the exhaust steam in the exhaust chamber 51 under the water reservoir. The valve 45 is provided with an operating stem 53 which extends through the front wall of the boiler and is provided with a handle 55. As shown by Fig. 1 the front wall of the boiler is provided with a semi-circular index with which the free end of the handle 100 co-operates to show various degrees of regulation of the valve.

100

The boiler is provided with a glass water gage 57. The lower end 59 of the filling funnel 23 is at a level at or near the lower part of the water gage 57 so that when the boiler has been filled to a level that will show on the gage the water will seal the filling funnel and prevent the escape of 110 steam therethrough.

110

According to the construction shown the burners serve also as parts of the stand on which the boiler is supported. The uprights 65 and 67 of this stand are connected 115 by horizontal pipes 61, 63, each pipe being provided with a series of perforations in its upper side to emit jets of gas. The standards 65 and 67 have horizontal ducts in communication with the pipes 61, 63, thus 120 providing an endless rectangular burner. Combustible gas is supplied through a Bunsen mixing device 69 having a gas cock 71 by which the admission of gas may be regulated.

120

As shown by Fig. 2 the bottom of the boiler is inclined from the front and back toward the middle to counteract the tendency of the hot gases to spread laterally and escape beyond the perpendicular limits of 120

the boiler. In fact, this formation tends to collect the heat at the middle of the boiler so that substantially all of the hot gases will pass through the flues 39. A damper 85 is arranged to regulate the size of the openings at the receiving ends of the flues so as to determine how much of the hot gases will flow to the treating chambers. This damper 85 is a plate of sheet metal having holes the same shape and size as the flues and arranged so that they will all register with the flues at once. The front and back edges of the plate are bent downwardly to stiffen it and to cooperate with parallel guides 87, 87 on the bottom of the boiler. A stud 83 is affixed to the damper and is straddled by a forked arm 81 which is one part of a lever. This lever has an arm 75 projecting from the front of the apparatus and serves as a handle by which the damper may be shifted for purposes of regulation. The lever is arranged on a fulcrum stud 73. A pointer 77 formed on the handle cooperates with a gage 79 to indicate the position of the damper.

When the shoes are in position for treatment the foreparts of the soles will be supported by the wire fabric 31 in the treating chambers but the heel ends of the shoes outside said chambers will be supported by a shelf 91. The shelf has trunnions 93 arranged in notches 95 formed in brackets 97. The shelf is otherwise supported by chains 101 anchored to hooks 99. The chains are adjustable relatively to the hooks to vary the inclination of the shelf as may be required by shoes of different styles.

Since the described apparatus has means 71 for regulating the supply of combustible gas, means 85 for regulating the flow of the hot products of combustion or other hot gases to the treating chamber, and means 45 for regulating the flow of hot moist vapor into the flues 39, the conditions in the treating chambers may be altered at will with regard to temperature and humidity to meet all the requirements of the various kinds of work that requires softening. The capacity of the burner is sufficient to heat the water to boiling, and as the quantity of water in the boiler diminishes by evaporation it may be quickly replenished from time to time by letting in small quantities of water from the reservoir 7 by opening the cock 21 for a few seconds. Although no exhaust flue is shown for taking away the exhaust gases and vapor from the apparatus it is obvious that a flue for this purpose may readily be attached to the back of the structure 5 in registration with the exhaust port 19. The inclination of the bottom 17 of the reservoir and of the top of the arched member 29 directs the exhaust gases and vapor from the front of the apparatus toward the rear, thus causing the flow to progress to-

ward the rear instead of permitting the gases and vapor to escape through the shoe-receiving openings. This induces a slight draft of cool fresh air into the treating chambers through the shoe-receiving openings and helps to guard against overheating the work.

An advantage in conducting the vapor into the flues 39 instead of conducting it directly from the boiler to the treating chambers is that the hot gases and vapor become thoroughly mixed before reaching the work. This avoids localization of hot dry gases on one part of the shoe and of excessively moist vapor on other parts. It is thus assured that all parts of the work will be treated uniformly. Furthermore, the areas of the treating chambers are not much greater than is necessary to accommodate the foreparts of the shoes, and for this reason the treating media, as they pass through the treating chambers are confined in very close relation to the work and therefore have relatively great treating efficiency.

If it is desired to restrict the escape of vapor and gases from the chamber 51 it can be done either by providing the exhaust flue with a damper or the damper may be associated directly with the exhaust port 19. For example, when it is desired to treat with hot dry gases exclusively or with only a relatively small proportion of moist vapor it may be in the interest of economy to restrict the escape through the exhaust port 19. Whatever water of condensation collects on the arched members 29 will flow down the sides of the latter instead of dropping on the shoes. A relatively great proportion of the heat of the exhaust vapor and gases has direct contact with the bottom of the reservoir 7 and the water in the reservoir is thus maintained at a temperature that requires comparatively little additional heat to make it boil.

As shown by Fig. 2 the uprights 65 and 67 of the stand are notched to receive the lower front edge of the boiler whereas the lower rear edge bears on plane horizontal surfaces and does not require any great degree of accuracy in proportioning the boiler and the stand to fit one into the other. Furthermore, the strap 9 and tightening bolts 11 serve not only to maintain the superstructure 5 in the desired relation to the boiler but serve also to secure the boiler to the stand so that the entire assemblage, including the three separable principal units, is all held intact by a single strap. The flues 39 are preferably inclined as shown by Fig. 2 so as to baffle the hot gases to some extent and therefore heat the water in the boiler more efficiently than if they were vertical.

Having thus described our invention, what we claim as new and desire to secure by Letters Patent of the United States is:

1. A shoe-treating apparatus comprising a treating chamber, combustion means, a flue arranged to conduct some of the products of combustion from said means into said chamber to treat the work therein, and vapor-generating means operable by said combustion means and arranged to supply hot moist vapor to said flue so as to mix it with said products of combustion.
- 10 2. A shoe-treating apparatus comprising a treating chamber, heat-generating means arranged to supply a current of hot gases to said chamber, and a water receptacle arranged to be heated by said means and arranged to mix hot moist vapor with said gases before they enter said chamber.
- 15 3. A shoe-treating apparatus comprising a treating chamber, a boiler, combustion means arranged to generate hot moist vapor in said boiler, a flue arranged to conduct some of the products of combustion from said combustion means to said chamber, and means arranged to conduct vapor from said boiler into said flue so as to mix the vapor with the products of combustion in the flue.
- 20 4. A shoe-treating apparatus comprising a treating chamber, a boiler, heat-generating means arranged under said boiler to generate hot moist vapor in the boiler, a flue arranged to conduct hot gases from said heat-generating means into said chamber, and means arranged to conduct hot moist vapor from said boiler into said flue to be mingled with said hot gases.
- 25 5. A shoe-treating apparatus comprising a treating chamber, a boiler, heat-generating means arranged under said boiler to generate hot moist vapor in the boiler, a flue intersecting said boiler to conduct hot gases from said heat-generating means to said chamber and to radiate some of their heat to the boiler while passing therethrough, and means arranged to conduct hot moist vapor from said boiler into said flue to be mingled with said hot gases.
- 30 6. A shoe-treating apparatus comprising a treating chamber, a burner, a fire-tube boiler arranged over said burner, one of the fire-tubes of said boiler being in communication with said chamber to supply products of combustion to the latter, and means arranged to conduct hot moist vapor from the interior of said boiler to the interior of said fire-tube to mix such vapor with said products of combustion.
- 35 7. A shoe-treating apparatus comprising a treating chamber, means for supplying hot moist vapor thereto, and means for generating said vapor and supplying hot products of combustion to the chamber.
- 40 8. A shoe-treating apparatus comprising a treating chamber, a boiler arranged under said chamber, a burner arranged under said boiler, a flue arranged to intersect said boiler to conduct products of combustion from
- burner to said chamber, means for regulating the volume of gases that may pass through said flue, and means for conducting hot moist vapor from said boiler to said chamber.
- 45 9. A shoe-treating apparatus comprising a plurality of treating chambers each formed and arranged to receive the forepart of a shoe, a boiler, a burner arranged under said boiler, a plurality of flues arranged to conduct products of combustion from said burner to said chambers respectively and arranged to intersect said boiler, and means forming communication between the steam space of said boiler and said flues respectively to supply hot moist vapor to said chambers.
- 50 10. A shoe-treating apparatus comprising a plurality of treating chambers each formed and arranged to receive the forepart of a shoe, a boiler, means for heating said boiler to generate steam therein, a trunk or manifold arranged in the boiler to receive hot moist vapor, and branches arranged to conduct said vapor from the trunk to said chambers respectively.
- 55 11. A shoe-treating apparatus comprising a treating chamber, a pressure-sustaining boiler adjacent thereto, heating means arranged to heat said chamber and boiler simultaneously, means for conducting some of the vapor from said boiler to said chamber, means for conducting some of said vapor elsewhere than to said chamber, and regulating means for varying inversely the proportions of vapor that may flow to said chamber and elsewhere.
- 60 12. A shoe-treating apparatus comprising a plurality of treating chambers, a pressure-sustaining boiler and means for heating the same to generate hot moist vapor, a trunk or manifold in communication with the vapor space of said boiler and having branches arranged to supply vapor to said chambers respectively, said trunk having an outlet to relieve the boiler pressure otherwise than through one or more of said branches, and regulating means arranged to vary inversely the proportions of vapor permitted to flow to said chambers on the one hand and through said outlet on the other hand.
- 65 13. A shoe-treating apparatus comprising a burner, a treating chamber arranged above the burner, a closed boiler arranged between the burner and the treating chamber and forming a flue to conduct products of combustion from the burner into the treating chamber, and means forming a conduit from the vapor space of the boiler to the treating chamber.
- 70 14. A shoe-treating apparatus comprising means including a burner for generating hot moist vapor, a treating chamber having an inlet for such vapor and an outlet for the used vapor, means arranged to conduct
- 75 80 85 90 95 100 105 110 115 120 125 130

vapor from said generating means to said chamber, and a reservoir for supplying said generating means with water to be converted into such vapor, said elements being organized to preheat the water in said reservoir by the used vapor issuing from said chamber and by waste products of combustion from said heater.

15. A shoe-treating apparatus comprising
 10 three separable cooperative structures formed to be stacked one upon another, the lowest of said structures including a burner, the intermediate structure comprising a boiler having an intersecting flue to conduct the
 15 products of combustion from said burner into the top structure, the latter comprising a treating chamber and above that a water reservoir, said chamber being formed and arranged to receive the products of combustion from said flue and to emit them against a wall of said reservoir, and means for conducting hot vapor from said boiler into said treating chamber, said reservoir and boiler having cooperative devices formed
 20 and arranged to replenish the boiler with water from the reservoir.

16. A shoe-treating apparatus comprising a boiler and a stand therefor having cooperative portions formed to fit one into another
 30 so as to permit separation, a unit formed to stand on said boiler and having a treating chamber, and releasable fastening means adapted to connect said stand and unit so as to keep the stand, the boiler and said
 35 unit intact in the aforesaid relations, and a burner arranged under said boiler, said elements being formed to supply the treating chamber with hot products of combustion from said burner and with hot moist vapor from said boiler.

17. A shoe-treating apparatus comprising a burner, a boiler over the burner, a treating chamber over a part of the boiler, an exhaust chamber over another part of the boiler, a water reservoir contiguous to a wall of said exhaust chamber, said elements being formed and arranged to cause hot products of combustion and hot moist vapor to flow from the burner and boiler respectively
 45 through the treating chamber and thence

into said exhaust chamber to heat the water in said reservoir, and means for conducting water from the reservoir to replenish the boiler.

18. A shoe-treating apparatus comprising
 a closed boiler, a series of treating receptacles arranged on top of the boiler and having open bottoms to admit treating media, a burner arranged under said boiler to generate hot moist vapor in the boiler, the latter
 60 having flues extending through it and registering with said open bottoms to conduct hot products of combustion from the burner to said receptacles, and means arranged to supply hot vapor from said boiler to said
 65 receptacles.

19. The herein described method which consists in causing combustion to generate hot moist vapor, mingling the products of such combustion and the hot moist vapor
 70 generated thereby, and simultaneously heating and moistening parts of a shoe by said media mingled as aforesaid.

20. The herein described method which consists in causing hot products of combustion to convert water into hot moist vapor, and causing said products of combustion and said hot moist vapor simultaneously to heat and moisten parts of a shoe.

21. A shoe-treating apparatus comprising
 80 a plurality of separate but closely related treating chambers, a pressure-sustaining boiler adjacent to said chambers, heating means common to said chambers and boiler, and means for supplying vapor from said
 85 boiler to said chambers individually.

22. A shoe-treating apparatus comprising a chamber to receive the work, a flue arranged to conduct treating media into said chamber, means to supply hot gases through
 90 said flue, means to supply hot moist vapor through said flue, and dampers arranged to control the admission of such hot gases and hot moist vapor to said flues so that each may
 95 be regulated independently of the other.

In testimony whereof we have signed our names to this specification.

FRED RICKS.

ALFRED EDWARD RICHARDS.
